* cited by examiner

Primary Examiner—Gary D. Watson*Assistant Examiner*—Cynthia Underwood(74) Attorney, Agent, or Firm—Brinks Hofer Gilson & Lione(57) CLAIM

I claim the ornamental design for a coffee maker, as shown and described.

DESCRIPTION

FIG. 1 is a top perspective view of a coffee maker of the present invention;

FIG. 2 is a front view thereof;

FIG. 3 is a first side view thereof;

FIG. 4 is a second side view thereof;

FIG. 5 is a top view thereof; and,

FIG. 6 is a rear view thereof.

The broken line showing of coffee maker is included for the purpose of illustrating environment and forms no part of the claimed design.
